UNITED STATES PATENT OFFICE.

PHILO B. TINGLEY, OF GLENRIDGE, NEW JERSEY.

TYPE-WRITER TABULATOR.

No. 852,988.

Specification of Letters Patent.

Patented May 7, 1907.

Application filed October 13, 1904. Serial No. 228,313.

To all whom it may concern:

Be it known that I, PHILO B. TINGLEY, a citizen of the United States, residing at Glenridge, county of Essex, State of New Jersey, 5 have invented a new and useful Type-Writer Tabulator, of which the following is a specification.

This invention relates to typewriting machines and particularly to mechanism for enabling such machines to be used with speed and accuracy when producing tabulated work; that is, columns of figures or words. Several mechanisms or attachments for attaining this result have been patented and 15 placed on the market, such devices or mechanisms involving the temporary release of the key-controlled feed so that the carriage will be rapidly propelled by its spring from right to left to a limit prescribed by what is called 20 tabulating stop, this movement or the mechanism which causes it being sometimes termed a "jump-feed."

It is to this class of invention that my present invention relates, and the particular object of this said invention is to provide improved means whereby the exact position in 25 which the carriage will be checked by a given stop may be instantly varied by the operator according to the number of characters comprising the group that is to form a line of the 30 column. For instance, when figures are to be written for statements of account, bills, invoices etc., the numerals in the groups comprising the column usually vary considerably, 35 and as the units must be written in a vertical line, and the tens, hundreds etc., similarly written, it is desirable for the sake of speed and accuracy that the machine shall have means for enabling the operator to determine at a 40 glance how far the carriage shall "jump" in order to write the first numeral of the group in the proper place.

Another object of the invention is to provide a mechanism for the purpose stated, 45 comprising a single variable stop adapted to co-act with one or more fixed but adjustable stops when brought to the desired position by the operator.

Other objects, relating to the general simplicity, efficiency and durability of the mechanism included in this invention, will be more fully apparent hereinafter.

My invention consists in the construction and combinations of parts substantially as 50 hereinafter described and claimed.

In the drawings hereto annexed, I have

illustrated a preferred embodiment, and a modification of my invention, in connection with sufficient of the parts of an "Underwood" type-writer to enable it to be readily understood by those skilled in the art. But it is to be understood that my invention is not limited to either the particular adaption or the exact details of the parts illustrated.

Figure 1 is a detail side elevation of a portion of an "Underwood" machine to which my invention in one of its embodiments has been applied. Fig. 2 is a sectional elevation showing the parts in a different position. Fig. 3 represents a view from the left of Fig. 7c 1. Fig. 4 represents a section on line 4-4 of Fig. 1. Fig. 5 is a view similar to Fig. 2 but illustrating a modification of that portion of the invention relating to the means for changing the position of the variable stop. Fig. 6 75 represents a section on line 6-6 of Fig. 5. Fig. 7 is a detail plan view of the variable stop and some of the immediately adjacent parts. Fig. 8 is a view similar to Fig. 7 but showing the variable stop after it has been 80 partially rotated and shifted along its supporting shaft by the carriage. Fig. 9 represents a section on line 9-9 of Fig. 7. Fig. 10 represents a section in line 10-10 of Fig. 8. Fig. 11 is a detail view of the separable 85 lever connections hereinafter described. Fig. 12 represents a section on line 12-12 of Fig. 11.

Similar reference characters indicate the same or similar parts throughout the several 90 views.

The frame of the machine is indicated at 20, and one of the rods for the carriage 21 is shown at 22. 23 indicates the feed rack which is carried by and travels with the carriage. 95 24 indicates one of the usual vibrating feed-dogs co-operating with the rack 23 to permit the step-by-step movement of the carriage. All of these parts are well known and need no further description or illustration.

Referring to Figs 1, 2, 3 and 7 to 10, a bar 25 having a series of vertical slots is secured at its ends to the frame of the machine and has its upper surface graduated or provided 100 with scale marks to correspond with the slots in the bar and, of course, corresponding with the usual scale (not shown) at the front of the machine. In one or more of the slots of bar 25 is placed a stop 26, the shape 105 of which is best shown in Figs. 9 and 10. I have shown but one such stop in Fig. 3 but it

is to be understood that as many will be carried by the bar 25 as there are columns to be written. The inner end of the stop 26 projects from the inner side of the bar, (see Figs. 8, 9 and 10) to co-act with the variable stop presently described. The stop is formed with an upwardly extending portion by which it may be grasped when its location is to be changed, and with a notch forming a shoulder that is engaged by a yielding stop-retaining bar 27. The ends of the bar 27 enter boxes 28 and are normally pressed upward by springs 29 in said boxes (see dotted lines in Fig. 3) so that said bar 27 will lock the stop or stops in position in the bar 25 by engagement with the shoulder of the stop. The lock-bar 27 may be depressed however to uncover the lower ends of the slots to permit the withdrawal or insertion of a stop 26 in the proper place to suit the work to be tabulated.

The variable stop which travels with the carriage comprises a sleeve or barrel 30 splined on a shaft 31 behind bar 25. Said shaft 31 is mounted in suitable bearings in the frame of the machine but having no endwise movement relatively to said frame, said shaft having a pinion 32 engaged by a toothed segment 33 carried by an arm 34 secured to a rock-shaft 35 mounted in bearings 36 on frame 20 (see Fig. 3). Said sleeve or barrel 30 is provided with a spiral flange 37 which is preferably, although not necessarily, stepped as shown, so as to abut against a stop 26 (see Fig. 8). The sleeve is also formed with a circumferential groove 38 which receives a block or lug 39 projecting from the carriage and traveling therewith. It will now be seen that the sleeve 30 and its spiral flange 37 constitutes a revolving and sliding variable stop, since it slides on the shaft 31 when the carriage travels, and revolves with the shaft 31 when the latter is actuated by the rack 33. And since the said stop and carriage travel in unison, the carriage will be stopped when a portion of the spiral flange 37 strikes a stop 26, and the particular scale point at which the carriage will stop will be determined by the amount of rotation that has been imparted to the shaft 31 and splined sleeve, through the medium of the rock-shaft 35 and rack 33.

Two embodiments of means for actuating the rock-shaft are illustrated and will be presently described, but before referring to either, it is essential that it be understood that the variable stop is capable of freely passing the stop or stops 26 whenever the machine is being used in the ordinary manner. As best shown in Figs. 8, 9 and 10, the flange 37 does not extend entirely around the sleeve and there is thus provided a space or path between the ends of the flange which will permit the variable stop to pass a fixed stop 26 when the former is in its normal posi-

tion which is that shown in Figs. 7 and 9. In order to hold the variable stop and the shaft 31 in this normal position, a spring 40 is connected to the arm 34 and the frame of the machine (see Fig. 1) so as to normally hold said arm against a suitable stop which may be a portion of the frame of the machine indicated at 41 in Fig. 2. Therefore when the arm 34 is in the position shown in Fig. 1 the rack 33 and pinion 32 hold the shaft 31 and sleeve 30 in such position that the latter will occupy the position shown in Figs. 7 and 9. But when the rock-shaft has been actuated by means such as presently described, so that the arm 34 is thrown out of normal position as indicated in Fig. 2, then the shaft 31 and the variable stop will be turned as indicated in Figs. 8 and 10 so that the carriage will be stopped by the contact of the flange 37 with a fixed stop 26. 85

The means shown in Figs. 1 to 4 for actuating the rock-shaft 35 to different degrees of rotative movement so as to vary the exact position at which the carriage will be stopped, comprise a series of push-rods 42 mounted in bearings 43 under the frame of the machine and having finger pieces or keys 44 which will be suitably marked to indicate units, tens, hundreds, etc. Each rod 42 also has a collar 45 adapted to engage the lower edge of a swinging gate or bar 46 pivoted at 47 to the frame of the machine and having an arm 48 at an angle thereto. Practically, the bar 46 and its arm 48 constitutes a bell-crank lever adapted to be actuated by any of the push rods. The arm 48 is connected by a link 49 to a pin projecting from the feed-dog 24 so that whenever a rod 42 is pushed into its farthest limit, its collar 45 actuates the bell-crank lever so as to pull down the dog 24 from the feed-rack 23 and thus release the carriage to permit the latter to be rapidly propelled by its spring in the manner usual with "jump-feed" devices. But before the push rod reaches its innermost position so as to release the carriage as mentioned, the rock-shaft 35 is actuated, by means which I shall now describe, to bring the variable stop out of its normal inoperative position. To this end, each rod 42 is pivotally connected to a lever 50 mounted to oscillate on a fulcrum rod 51 extending across the back of the frame. Secured to and depending from the rock-shaft 35 are as many arms 52 as there are levers 50 and rods 42. The upper arm of each lever 50 is provided with a plate having a hook 53, said plate being secured to its lever by a bolt 54 or other equivalent fastening passing through a slot in the lever whereby the position of the hook may be adjusted toward or from the fulcrum of the lever. Each arm 52 has a slot in which a pin 55 is adjustably secured relatively to the fulcrum of the arm in a manner similar to the adjustment provided for the hook 53 on its lever. 125 130

The pin 55 extends past the edge of the adjacent lever 50 so as to be engaged by the latter when rod 42 is pushed in, thereby causing the parts to move from the position shown in Fig. 5 1 to that shown in Fig. 2, the variable stop being thus rotated to an amount corresponding to which arm 52 is actuated and the point at which the pin 55 is set along its arm. As shown in Fig. 3, the location of the pins 10 55 of the different arms 52 vary. This is to vary the amount of movement that will be imparted to the rock-shaft and the variable stop by the different push-rods.

As shown in Fig. 2, the hook 53 engages 15 the pin 55 in such manner as to lock the key or push-rod and the rock-shaft at the end of the stroke to limit the movements of all the parts and also prevent over-throw of the rock-shaft and the variable stop due to 20 momentum.

The construction described enables any one of the tabulating key rods to be actuated without affecting the others, owing to the fact that there is no permanent connection 25 between the levers 50 and arms 52 of each pair. While all of the arms 52 will oscillate with the rock-shaft only one lever 50 will be moved. And when one lever 50 is in the position shown in Fig. 2 no other lever 50 can 30 be operated so as to affect the variable stop because the hook 53 of the actuated lever locks the rock-shaft by engaging the pin 55 of the actuated arm 52.

In Figs. 5 and 6 the levers which actuate 35 the arms 52 are arranged to be operated by a downward instead of an inward finger movement. In said figures where the parts are for the same purpose as similar parts in the other figures, I employ the same numerals 40 with the addition of a cipher. In said figures, the arms 520 are longer than the arms 52 in the other form, and extend inward from the rock-shaft 35 instead of downward, and are provided with pins 550. The levers 45 500 are mounted on fulcrum rod 510 extending under the machine, and at their inner ends carry the plates having hooks 530, said plates being adjustably secured by bolts 540 passing through the slots of the lever. The 50 hooks 530 and pins 550 are adjustable along their slotted levers in the same manner and for the same purpose described in connection with hooks 53 and pins 55. The outer ends of the levers 500 are provided with vertical 55 push-pieces 420 extending upward through a guide plate 430 and having finger pieces or keys 440. Mounted on the rod 510 is a rectangular lever-frame 56 having its front bar extending under the front portions of all the 60 levers 500 and having a link 490 connecting its rear bar with one end of a short lever 57 pivoted at 58 to a suitable fixed part or projection of the frame of the machine. The other end of the short lever 57 has a pin 59 65 adapted to contact with a pin 60 projecting

from the feed-dog 24. In this form the connections are such that upon the depression of a key 440, the rock-shaft 35 is first actuated to vary the position of the variable stop, which will be the same as in the other form 70 first described, and then the lever frame will be actuated to lift the link 490 and cause the pin 59 of lever 57 to disengage the feed-dog 24 from the rack 23 and permit the carriage to "jump" as far as permitted by the stops 75 which are supposed to be as shown in Figs. 7 to 10.

In Figs. 11 and 12, I have illustrated on a somewhat enlarged scale a portion of the arms 52 and of the levers 50. In Fig. 11 80 the arm 52 and a lever 50 are shown by full lines in horizontal positions. This is for convenience of illustration, and it will be understood that Fig. 11 should be turned 1/4 to the right if it is to be compared with the 85 form shown in Fig. 2. Said Figs. 11 and 12 show in full lines how the pin 55 is engaged by the edge of the lever 50 so that the former will be actuated by the latter. The dotted lines in Fig. 11 represent these parts when 90 they have been moved to the locked position hereinbefore described.

Since the portions of the several parts of the mechanism have been described in connection with the descriptions of the parts 95 themselves, a summary or complete description of the mechanism as a whole will not be necessary.

Having now described the invention, and illustrated the same in what I consider to be 100 the best form or forms in which the said invention may be embodied although without attempting to illustrate or describe all of the forms in which the invention may be embodied, I declare that what I claim is:— 105

1. A tabulating mechanism for type-writing machines comprising one or more fixed stops, a variable stop to co-act therewith and means for changing the position of the variable stop, said means including levers 110 having overlapping portions provided with adjustable means for transmitting motion from one to the other.

2. A tabulating mechanism for type-writing machines comprising one or more 115 fixed stops, a variable stop to co-act therewith and means for changing the position of the variable stop, said means including levers having overlapping portions, one of said overlapping portions having a pin projecting 120 from it, and the other having a hook to engage said pin and lock the parts against further movement.

3. A tabulating mechanism for type-writing machines comprising one or more 125 fixed stops, a variable stop to co-act therewith and means for changing the position of the variable stop, said means including levers having overlapping portions, said overlapping portions being slotted and having re- 130

spectively adjustably connected therewith a pin and a hook to engage said pin.

4. A tabulating mechanism for type-writing machines comprising a fixed bar having a series of openings, a stop adapted to project through any one of said openings, a box near each end of said bar and containing a spring, a retainer bar having its ends resting on the springs in the boxes, said bar crossing the openings of the fixed bar to retain the stop in place, a stop connected with the carriage, and means for releasing the carriage.

5. A tabulating mechanism for type-writing machines comprising a rock-shaft having a plurality of arms each having a pin, a corresponding plurality of levers each adapted to engage a pin of an arm, the points of engagement varying for different co-acting arms and levers, a variable stop and connections whereby it will be actuated by said rock-shaft, a fixed stop, and independent means for actuating the said levers.

6. A tabulating mechanism for type-writing machines comprising a rock-shaft having a plurality of arms each having a pin, the pins being set at different distances from said shaft, a corresponding plurality of levers adapted to individually engage said pins and each having a hook to contact with such pin, a variable stop and connections whereby it will be actuated by said rock-shaft, a fixed stop, and independent means for actuating the said levers.

7. A tabulating mechanism for type-writing machines comprising a rock-shaft having a plurality of arms each having a pin adjustably connected therewith, a corresponding plurality of levers having hooks adjustably connected therewith, each lever being adapted to act against a pin of an arm to actuate the rock-shaft until the hook of that lever engages the pin of the corresponding arm, a variable stop and connections whereby it will be actuated by said rock-shaft, a fixed stop, and independent means for actuating said levers.

8. A tabulating mechanism for type-writing machines comprising a fixed slotted bar, one or more stops removably mounted in said bar, a shaft, a sleeve splined on the shaft and having a spiral flange and connected with the carriage to travel therewith, independent key-controlled devices having connections for actuating the said shaft, a carriage release dog, a link having connections at one end for actuating said dog, a lever connected with the other end of said link, and means whereby movement of either one of the key-controlled devices will actuate said lever.

In testimony whereof I affix my signature, in presence of two witnesses.
